UNITED STATES PATENT OFFICE.

THOMAS G. PLANT, OF BOSTON, MASSACHUSETTS, ASSIGNOR TO UNITED SHOE MACHINERY COMPANY, OF PATERSON, NEW JERSEY, A CORPORATION OF NEW JERSEY.

LASTING-MACHINE.

1,126,856.

Specification of Letters Patent.

Patented Feb. 2, 1915.

Original application filed September 28, 1908. Serial No. 455,159. Divided and this application filed May 2, 1910. Serial No. 558,915.

To all whom it may concern:

Be it known that I, THOMAS G. PLANT, a citizen of the United States, residing at Boston, in the county of Suffolk and State 5 of Massachusetts, have invented an Improvement in Lasting-Machines, of which the following description, in connection with the accompanying drawings, is a specification, like letters on the drawings 10 representing like parts.

The invention to be hereinafter described relates to lasting machines, and more particularly to the end pads and their supporting means; the present application being a 15 division of a prior Patent, No. 958,280, dated May 17, 1910.

As well understood by those skilled in the art, lasting machines of the general character referred to in said prior application 20 are provided with flexible chains for embracing the ends of the lasted shoe, and such flexible chains are usually provided with a facing of leather or the like, whereby abrasive action injurious to the finish 25 of the upper by the chain is avoided. It frequently becomes necessary to remove the leather facing or pad, and yet so support it from the flexible chain that it shall perform its function effectively. With these facts in 30 mind the present invention aims to provide means for detachably connecting the facing pad to the flexible chain, so that while readily detachable therefrom it may be clasped about the end of the shoe and given 35 its characteristic movements, as set forth in said prior application, all of which will be more clearly understood from the following description and accompanying drawings of one form of means for carrying the invention 40 into effect, it being understood that the invention is not restricted to the particular details of said means, but is definitely pointed out by the claims.

In the drawings:—Figure 1 is a plan 45 view in partial section of an end lasting chain and its supporting elements having a pad connected thereto, unnecessary portions of the lasting machine being omitted to avoid complication; Fig. 2 is an elevation 50 of the parts shown in Fig. 1, looking in the direction of the arrow, Fig. 1, some of the parts being broken away to more clearly disclose those beyond; Fig. 3 is a transverse section on the line 3—3 of Fig. 2; Fig. 4 is

a detached perspective view of the lasting 55 pad or facing; and Fig. 5 is an enlarged detail in perspective showing the means for attaching the ends of the facing or pad to its supports.

The movable bars 1, Fig. 1, sliding on the 60 side supports 2 of the lasting head, and having pivoted at 3 the arms 4, the spring 5 connected to the ends of the arms 4 for normally maintaining them in the position indicated in Fig. 1, the end wipers 6, Fig. 2, 65 and the means for operating the wipers and movable bars 1 may be and preferably are substantially the same as the corresponding parts shown and described in said prior application to which reference may be 70 had.

Flexibly connected to the ends of the arms 4 at 7 is the flexible chain 8, and extending from the central portion of the chain 8 is a central supporting arm 9, Figs. 75 1 and 3, the construction being such that while the ends of the chain may be moved by the arms 4 to properly clasp the chain about the end of the shoe, the central support 9 will sustain the central portion of 80 the chain to maintain it in proper coacting relation with the end of the shoe to be treated, as will be readily understood.

As pointed out in said prior application, the machine is preferably provided with a 85 toe rest 10, Fig. 3, supported on the standard 11: said parts however, forming no part of the present invention, do not need further description here, as they are fully described and illustrated in the application 90 mentioned.

Depending from the ends of the arms 4 are the clips 12, Fig. 5, preferably formed with a turned upper portion 13 provided with an opening 14 through which a suitable pin may be passed, as indicated in Fig. 2, for connecting each clip 12 flexibly to the end of its supporting arm 4. Obviously various means may be employed for sustaining the clips 12, but that herein specified has been found to be a convenient character of means for this purpose. 95

Each clip 12 is provided with a slot 15, Fig. 5, which is adapted to receive the shouldered portion 16 of a coacting lug 17 secured, as indicated in Figs. 4 and 5, to the flexible pad or facing 18, the construction being such that the shouldered portion 16 100

105

of the lug 17 may be slid lengthwise into the slot 15 of the clip 12, and an upward extending portion of the lug 17 will prevent sidewise or lateral detachment of the 5 clip and lug, as will be readily understood.

Secured to the central rear portion of the pad on the exterior thereof is a plate 19, having its lower end portion preferably turned toward the interior of the pad, as 10 indicated in Figs. 3 and 4, and provided with an opening 20, said plate 19 being secured to the pad by any suitable means, such as the rivets or lug devices 21.

Projecting centrally from the rear or 15 outer surface of the pad 18 is a pin 22, Figs. 3 and 4, which is adapted to engage a suitable recess or opening in an arm 23 supported by the flexible chain 8, the construction being such that when the pad has the 20 clips 12 and lugs 17 in coacting relation and the pin 22 seated in the central opening of the arm 23, the pad will be held in proper position with respect to the flexible chain.

Secured to the flexible chain 8, preferably 25 by means of the arm 23, is the shelf or bottom support 24 for the pad 18, said support being preferably formed in U or segmental shape, as indicated in Fig. 3, and of a dimension to properly sustain the lower edge 30 of the pad 18 when the latter is in operative position.

The bottom support 24 is provided with a pin 25 extending upward therethrough, the upper end of said pin, as shown in Fig. 3, 35 being adapted to engage the opening 20 in the plate 19 for maintaining the pad in its working position with the clips 12 and lugs 17 in proper engagement. The pin 25 extends through an opening in the bottom 40 support 24 and is surrounded by a spring 26, the upper end of which is seated against a collar 27 secured to the pin and the lower end of which rests upon the shouldered portion of the opening in the bottom support, 45 the construction being such that the tendency of the spring is to force the pin 25 upward into engagement with the hole 20 of the plate 19.

Obviously the particular construction 50 may be varied within the true scope of the present invention, and the pin 25, which for identification may be termed a latch, may be otherwise formed and caused to coact with a part other than the hole 20 to 55 hold the pad in its proper position with respect to the chain with the clips and lugs in coacting relation; and it is also obvious that the clips 12 and lugs 17 might be differently arranged and differently sustained to maintain 60 the end portions of the pad in proper coacting relation with the end portions of the chain.

From the construction hereinbefore described and the various modifications which 65 may suggest themselves to one skilled in the

art, it will be apparent that the pad 18 may be readily disengaged from the flexible chain by simply withdrawing the latch or pin 25 and moving the pad endwise to the right, Fig. 3. Similarly the pad or another one in lieu thereof may be readily connected to the flexible chain by simply moving the shouldered portion 16 of the lugs 17 into coacting relation with the slots 15 of the clips 12 and causing the latch 25 to engage 70 the plate 19 or other device; and it will be readily understood that while the pad is thus held detachably connected to the chain for movement therewith as the chain is caused to embrace the end of the shoe, as 80 pointed out in said prior application, the connection of the pad with the chain is such that the wiping or upward movement of the pad about the end of the shoe will not cause displacement of the pad with respect to the chain by reason of the supporting connections between the two. It will also be apparent from the construction described that the end portions of the facing pad, while supported in operative position 90 with reference to the flexible member, are free to move relative to said flexible member in a direction toward and from the end thereof without disengagement of the clips and lugs. This adaptability is of importance 95 because as the flexible member and pad close about the end of a shoe, a relative sliding movement takes place with respect to the end portions of each, as will be readily understood by those skilled in the art, and the elongated slot of the clip and its coacting shoulder on the lug permit such relative movement while preventing disarrangement or disengagement of the parts.

What is claimed is:

1. In a lasting machine, the combination 105 of a flexible band adapted to conform to the end of a shoe, a facing pad for said flexible band presenting an unobstructed shoe engaging surface, means for supporting the flexible band and pad, and means slidably connecting the band and pad for relative movement in assembling the parts in operative relation.

2. In a lasting machine, the combination 110 of a flexible member adapted to conform to the shape of a shoe at the end thereof, a detachable facing pad for said flexible member, means for connecting the central portion of the pad with said flexible member, and means exterior with relation to the inner face of the pad and having sliding engagement therewith for supporting the ends of the pad.

3. In a lasting machine, the combination 115 of a flexible member adapted to conform to the shape of the end of a shoe, supporting arms connected to the end portions of said flexible member, a detachable facing pad for said flexible member, coacting clips and lugs 120

125

130

for supporting the end portions of the detachable facing, detachable connections between the flexible member and central portion of the facing, and a latch for holding 5 said parts in coacting relation.

4. In a lasting machine, the combination of a flexible member adapted to conform to the shape of the end of a shoe, supporting arms connected to the end portions of said 10 flexible member, a detachable facing pad for said flexible member, coacting clips and lugs for supporting the end portions of the detachable facing, detachable connections between the flexible member and central portion 15 of the facing, and means movable with the flexible member for supporting the lower edge of the pad.

5. In a lasting machine, the combination of a flexible member extending from side to 20 side about the end adapted to conform to the shape of the end of a shoe, a facing pad for said flexible member, supports for the ends of the flexible member and facing pad, and means supporting the pad at the exterior thereof permitting relative endwise 25 movement of the flexible member and facing pad as they are closed about the end of a shoe.

6. In a lasting machine, the combination 30 of a flexible member adapted to conform to the shape of the end of a shoe, a detachable facing pad for said flexible member, means for detachably connecting the facing pad in operative position with respect to the flexible 35 member, a bottom support for the facing pad, and a latch for holding the facing pad in place with respect to the flexible member.

7. In a bed lasting machine, the combination 40 of a flexible chain, a pad of flexible material, devices for detachably connecting the end portions of the pad to its supports, a bottom support to sustain the lower portion of the pad, and means for detachably 45 connecting the pad and chain.

8. In a bed lasting machine, the combination 50 of a flexible chain or member, supporting means therefor, a facing pad, end clips having slots and end lugs having portions to detachably engage the said slots to maintain the facing pad in position, means for detachably engaging the center portion of the flexible chain or member and facing pad, and a latch for holding said parts in 55 coacting relation.

9. In a lasting machine, the combination 60 of a flexible member adapted to conform to the end of a shoe, supports for said flexible member, a facing pad, and means for detachably associating the flexible member and pad, said means having sliding members to permit relative end movement of the flexible member and pad as they close about the end of a shoe.

65 10. In a lasting machine, the combina-

tion of a flexible member adapted to conform to the end of a shoe, supporting arms connected to the flexible member for supporting it, a facing pad for said flexible member, and supporting devices for the 70 ends of the pad adjacent the ends of the flexible member, said supporting devices having members permitting relative longitudinal movement of the ends of the pad and flexible member as they close about the 75 end of a shoe.

11. In a lasting machine, the combination of a flexible member adapted to conform to the end of a shoe, supporting arms connected to the flexible member for supporting it, a facing pad for said flexible member, and relatively movable clips and lugs for supporting the ends of the facing pad to permit relative longitudinal movement of the end portions of the pad and flexible 85 member as they are closed about a shoe.

12. In a lasting machine, the combination of a flexible member adapted to conform to the end of a shoe, supporting arms connected to the end portions of said flexible member, a facing pad for said flexible member, and means between the supporting arms and pad for supporting the end portions of the pad, said means comprising a part movable with respect to the end of the 95 flexible member to permit relative longitudinal movement of the pad and flexible member as they are closed about the end of a shoe.

13. In a lasting machine, the combination 100 of a flexible chain member adapted to conform to the shape of the end of a shoe, supporting arms connected to the end portions of said chain member, a detachable facing pad for said flexible chain member, and coacting clips and lugs for supporting the end portions of the detachable facing, said clips and lugs being relatively movable to permit the ends of the chain member and pad to move relatively as they close about a shoe. 105

14. In a lasting machine, the combination 110 of a flexible member adapted to conform to the shape of the end of a shoe, supporting arms connected to the end portions of said flexible member, a detachable facing pad for said flexible member, and a sliding connection between the supporting arms and facing pad permitting the end portions of the pad to move longitudinally with relation to the ends of the flexible member as 115 said member and pad are closed about the end of a shoe.

15. In a lasting machine, the combination 120 of a flexible member adapted to conform to the shape of the end of a shoe, a facing pad for said flexible member, and means for maintaining the flexible member and pad in assembled relation said means comprising interengaging and relatively movable parts and permitting relative end move- 125

ments of the flexible member and pad as they close about the end of a shoe.

16. In a device of the character described, the combination of a flexible member 8 adapted to conform to the end of a shoe, a flexible pad 18, clips 12, and lugs 17 engaging the clips to support the ends of the pad.

In testimony whereof, I have signed my name to this specification, in the presence of two subscribing witnesses.

THOMAS G. PLANT.
